GEORGE H. DAVIS, OF STONY BROOK, NEW YORK.

Letters Patent No. 89,635, dated May 4, 1869.

IMPROVEMENT IN STEERING-APPARATUS.

The Schedule referred to in these Letters Patent and making part of the same.

To all whom it may concern:

Be it known that I, GEORGE H. DAVIS, of Stony Brook, in the county of Suffolk, and State of New York, have invented a new and useful Improvement in Steering-Apparatus; and I do hereby declare that the following is a full, clear, and exact description thereof, which will enable others skilled in the art to make and use the same, reference being had to the accompanying drawings, forming part of this specification.

This invention relates to a new and useful improvement in apparatus for steering vessels on the water, and consists in constructing and arranging a chain-pulley in such a manner, that a chain may be effectively used in combination with a traversing-wheel, as will be hereinafter more fully described.

In the accompanying plate of drawings—

Figure 1 represents a perspective view of the stern of a vessel with my steering-apparatus attached.

Figure 2 is a section of the chain-pulley.

Similar letters of reference indicate corresponding parts.

My invention is designed to apply to that class of steering-apparatus where a traversing-frame and wheel are attached to the rudder-post, and more generally in use on the smaller class of vessels, as sloops and schooners, the rudder being moved directly thereby, while all the apparatus connected therewith is on the deck of the vessel, and under the eye of the helmsman or pilot.

I am aware that it is not new, or patentable to substitute a chain for a rope in this description of service, but I am not aware that a chain-pulley has been used in combination with a traversing-wheel, or any other steering-wheel, so constructed as to effectually prevent the slipping of the chain on its pulley.

A is the rudder-post,

B is the traversing-frame, and

C is the steering-wheel.

D is the windlass-drum, around which the rope is wound in the steering-apparatus in common use.

To this windlass or drum I attach my chain-pulley, E. This I have so constructed that it may be applied to the ordinary windlasses now in use.

This pulley is made of cast-iron, with a deep V-shaped groove or channel in its face or periphery, the sides of which groove are recessed out, as seen in fig. 2, so as to fit the links of the chain, and to most effectually prevent the slipping of the chain.

In using a rope over the drum in this manner, great inconvenience is experienced from the constant stretching of the rope. Every time the rudder is turned, a quantity of "slack" has to be taken up before the rudder feels the movement of the wheel, and where the chain is used, if the chain "slips" over the pulley or windlass, the difficulty is quite as great.

In the use of my chain-pulley there is no "slip," and there can be no "slack."

The safety of the vessel, and the lives of those on board frequently depends upon the rudder. It is consequently of the utmost importance that the apparatus by which it is operated should be made instantly effective, and be of the most durable character as regards its construction.

Having thus described my invention,

I claim as new, and desire to secure by Letters Patent—

In combination with the steering-wheel and windlass C D, or their equivalents, the chain-pulley E, constructed as described, and for the purposes set forth.

GEORGE H. DAVIS.
